(57) **CLAIM**

We claim the ornamental design for a washing machine, as shown and described.

DESCRIPTION

FIG. 1 is a front perspective view of a washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view of the washing machine shown in an alternate position;

FIG. 9 is an exploded view of the washing machine in which the detergent container is shown separated from the body of the washing machine; and,

FIG. 10 is an enlarged exploded view of the claimed portion shown in FIG. 8 to show that each detergent container can be removed.

The broken lines in the figures show portions of the washing machine which form no part of the claimed design.

The dot-dash broken lines in the figures represent an unclaimed boundary line and form no part of the claimed design.
